UNITED STATES PATENT OFFICE

2,446,160

URINE SAMPLER ATTACHMENT

Gertrude A. Muller, Fort Wayne, Ind., assignor to
The Toidey Company, Gertrude A. Muller, Inc.,
a corporation of Indiana

Application September 11, 1946, Serial No. 696,107

3 Claims. (Cl. 4—1)

1

This invention relates to improvements in a urine sampler attachment for toilets adapted for collecting samples of urine from a person while seated upon a toilet.

It has become a custom to apply to the seat of an ordinary toilet an auxiliary seat for infants by superimposing it upon the regular seat for adults, and also there is commonly used in connection with the auxiliary seat a deflector adapted to intercept and deflect liquid, expelled by a male infant while seated, into the bowl of the toilet.

One of the objects of the instant invention is the provision of a urine sampling vessel that is readily attachable for support to the deflector while positioned below the toilet seat within the bowl so as to receive liquid discharged directly from a person seated on the toilet, or indirectly by drainage from the deflector, and easily detachable for removal of the sample collected in the vessel.

Another object of the invention is to provide a liquid sampling vessel that is conveniently placed in operative position in connection with the toilet or adjuncts thereof, and readily removable therefrom after receiving a sample of the expelled liquid.

Other objects and advantages of the invention appear in the following description.

An illustrative embodiment of the invention is shown in the accompanying drawings, in which:

Fig. 1 is a side elevational view of a urine deflector supported upon an auxiliary seat for a child and a sampling vessel supported in operative position in connection with the deflector, the showing of the auxiliary seat being fragmentary and in section;

Fig. 2 is a perspective view of a sanitary deflector similar to a known type and modified suitably for the present purpose of attaching the sampling vessel thereto;

Fig. 3 is a perspective view of the sampling vessel;

Fig. 4 is a fragmentary transverse cross-sectional view of an ordinary toilet with the sampling vessel supported in operative position therein and a modified support therefor; and

Fig. 5 is a fragmentary elevational view of the sampling vessel in place projected from Fig. 4 in a plane at right angles thereto.

The illustrative embodiment of the invention consists of a urinary deflector, indicated generally by A, that is attachable to an auxiliary child's toilet seat 6. The deflector preferably is made of a suitable semi-pliant waterproof

2

plastic material shaped to have a vertically elongated rear open cavity 7, a closed front wall 8, side walls 9 provided with lateral outwardly extending slotted lugs 10, a drain partition 11 connected with the side and front walls of the deflector, externally projecting blocks 12 adjacent the lugs 10, and a centering stud 13 projecting rearwardly from the lower end portion of the front wall 8 of the deflector.

10 The sampling vessel, indicated generally by B, has side walls 14 provided with exterior vertically extending spaced ribs 15, constituting guides, a contiguous rear wall 16 in which is formed a spout 17, and a front wall 18 that extends upwardly beyond the side walls, the upper end of which has a forwardly projecting ledge 19, there being formed in the front wall a forwardly projecting enlargement constituting a saddle 20 provided with an arched cavity 21 in its lower extremity. The side walls 14 have at their forward ends upwardly extending continuations constituting arms 22 that project forwardly beyond the front wall 18. The upper ends of the arms have fingers 23, and gaps 24 are located 15 between the ends of the ledge 19 and the corresponding inner faces of the arms 22.

15 In Fig. 4 is shown a modified support for the sampling vessel B, which preferably consists of a bar 25 having a U-shaped yoke 26 made in its midportion, and arms 27 that spread outwardly therefrom, the distal terminals of which rest upon the rim of the toilet bowl 28 beneath the adult seat 29. When the vessel is lodged in the yoke with the guides astride the sides thereof, 20 and with the outer terminals of the bar resting upon the rim of the bowl, the vessel is sustained 25 in receptive position in the toilet.

When the vessel is used in supported connection with the deflector, the deflector is positioned 40 on the front end of the child's seat 6 with the flange 6' on the seat projecting into slots 30, made in the side walls 9 of the deflector, located above the partition 11. The vessel B is then detachably connected with the lower end portion of the deflector by positioning the ledge 19 beneath the partition 11, the fingers 23 extending in front of the blocks 12, and with the saddle resting upon the centering post 13 which then projects into the cavity thereof. In this manner the vessel 45 is sustained in position within the toilet bowl for reception directly of liquid expelled by a person seated on the auxiliary seat, or, indirectly by drainage from the deflector.

50 The usefulness of the appliance thus constructed is realized in the convenience to an at-

tendant in obtaining samples of urine for subsequent analysis without perturbation or concern of a patient while seated on the toilet.

Variations from the particular construction above disclosed may be resorted to by the exercise of skill in the art, without departure from the spirit or scope of the invention.

What I claim is:

1. A toilet attachment for obtaining samples of urine from persons while seated on the toilet, for subsequent analysis, a child's auxiliary seat superimposed upon the adult seat of the toilet, a deflector detachably secured on the front end of the auxiliary seat disposed to normally drain into the bowl of the toilet, and provided with a partition connecting the front and side walls of the deflector and a centering stud projecting rearwardly from the lower portion of said front wall, and a sampling vessel having arms provided with fingers engageable with blocks on the deflector, a saddle on the front wall engageable with said stud, and a forwardly extending ledge on the upper end of said front wall disposed beneath said partition when the vessel is in place, there being slots located between the ends of the ledge and adjacent faces of said arms for reception of the corresponding side walls of the deflector.

2. An attachment for a toilet adapted to obtain samples of urine from a person while seated on the toilet, a child's auxiliary seat removably disposed on the adult seat of the toilet, provided with a deflector adapted to drain into the bowl of the

toilet, and having a transversely disposed partition, and a sampler consisting of a vessel removably engageable with said deflector having a ledge that extends beneath said partition when the deflector and the vessel are engaged, the arrangement being such that the vessel, when in place, is adapted to receive directly liquid expelled by a person seated on the toilet, or indirectly by drainage from the deflector.

3. In combination, a toilet provided with an adult seat, an auxiliary child's seat superimposed upon the adult seat, a urine deflector removably positioned on the front end of the child's seat adapted normally to drain into the bowl of the toilet, and provided with a transverse partition in its cavity, and a urine sampler consisting of a vessel removably supported on the deflector, disposed when in place within said bowl, the arrangement being such that the vessel is adapted to receive directly liquid expelled by a child seated on the auxiliary seat, or indirectly by drainage from the deflector.
